(57) CLAIM

I claim the ornamental design for a cookie dunk cup, as shown and described.

DESCRIPTION

FIG. 1 is an upper perspective view of a cookie dunk cup showing my new design;
FIG. 2 is a first side view thereof;
FIG. 3 is a second side view thereof;
FIG. 4 is a top view thereof;
FIG. 5 is a bottom view thereof;
FIG. 6 is a cross-sectional view thereof, taken along line 6:6 of FIG. 2;
FIG. 7 is a cross-sectional view thereof, taken along line 7:7 of FIG. 3; and,
FIG. 8 is a lower perspective view thereof.
